WIRE TYING MACHINE

Parvin Wright, Seattle, Wash., assignor to The
Stanley Works, New Britain, Conn., a corpora-
tion of Connecticut

Application January 3, 1939, Serial No. 249,127

32 Claims. (Cl. 100—31)

This invention relates to machines for twisting a knot in overlapped portions of a wire in the securing of packages, and has for its object to provide a construction of an automatic type which is simple in parts and more efficient in operation than those heretofore proposed.

With these and other objects in view the invention resides in the novel details of construction and combinations of parts as will be disclosed more fully hereinafter and particularly pointed out in the claims.

Referring to the accompanying drawings forming a part of this specification and in which like numerals designate like parts in all the views—

Fig. 1 is a vertical side elevational view of the machine with various parts shown somewhat diagrammatically, the purpose being to show the general assembly of parts and their approximate relationships;

Fig. 2 is a vertical front elevational view of the machine with some of the operating parts omitted and others shown somewhat diagrammatically;

Fig. 3 is a detail diagrammatic view to illustrate a mechanism for interrupting the feed of the packages to be banded;

Fig. 4 is a detail view partly in section and partly in elevation to illustrate the arrangement and operation of the mechanism for feeding the wire to and from the twister mechanism, said view taken as on the line 4—4 of Fig. 5 and looking in the direction of the arrows;

Fig. 5 is a detail view partly in section and partly in elevation to illustrate mainly the arrangement and operation of the wire feed rolls, said view taken as on the line 5—5 of Fig. 4 and looking in the direction of the arrows;

Fig. 6 is a side elevational view of the twister mechanism and its associated parts;

Fig. 7 is a detail view partly in section and partly in elevation, taken as on the line 7—7 of Fig. 6 and looking in the direction of the arrows, and illustrating the twister mechanism and its associated parts;

Fig. 8 is a detail view partly in section and partly in elevation, taken as on the line 8—8 of Fig. 6 and looking in the direction of the arrows, and illustrating the twister mechanism and its associated parts;

Fig. 9 is a detail view partly in section and partly in elevation to illustrate the operation and arrangement of the wire feed rolls, said view taken as on the line 9—9 of Fig. 4 and looking in the direction of the arrows;

Fig. 10 is a detail view partly in section and partly in elevation to illustrate a clutch device for controlling the operation of the twister mechanism;

Fig. 11 is a detail view of a portion of the clutch mechanism shown in Fig. 10, said view taken as on the line 11—11 thereof and looking in the direction of the arrows;

Fig. 12 is a foreshortened view partly in section and partly in elevation to illustrate the control mechanism by which the wire is fed by the feed rolls first in one direction and then in the opposite direction;

Fig. 13 is a detail elevational view illustrating the clutch device shown in Fig. 10, as well as the means for tensioning the wire around the package and holding the wire so tensioned;

Fig. 14 is a vertical transverse sectional view taken as on the line 14—14 of Fig. 1 and looking in the direction of the arrows, and illustrates the means for holding the tensioned wire during the twisting operation;

Fig. 15 is a plan view partly in section and partly in elevation, taken as on the line 15—15 of Fig. 13 and looking in the direction of the arrows, said view to illustrate the construction of the means for tensioning the wire;

Fig. 16 is a detail plan view mostly in section to illustrate the lower or gripping portion of the tensioning device shown in Fig. 15;

Fig. 17 is a detail view illustrating the latch and the release therefor used in connection with the mechanism for elevating a package to a position where the applied wire is twisted about said package, said view taken as on the line 17—17 of Fig. 1 and looking in the direction of the arrows;

Fig. 18 is a detail view showing a modification of the means for elevating a package to wire twisting position;

Fig. 19 is a plan view in more or less diagram to illustrate the drive connections for the wire feed rolls;

Fig. 20 is a partial perspective view illustrating a portion of the twisting mechanism; and

Fig. 21 is a view of the completed and twisted knot.

This invention covers an automatic machine for tying a wire band around a box or other package and comprises generally a twister head with associated cutters for severing the bights of the wire after the knot has been completed and means for positively ejecting the twisted knot from the twister pinion, as well as feed mechanism for first passing the wire from a reel to and around (as a loop) the package to be banded.

and then shifted to operate for drawing the slack out of the loop, means for tensioning the wire after the slack has been removed from the loop, and cooperating mechanisms for synchronizing the various operations.

The machine is provided with suitable framework constituting a support for the various mechanisms, the numeral 2 generally designating the top plate or bed of the machine and to which 10 most of the mechanism is supportedly attached, 3 indicating generally the twister mechanism, 4 an electric motor or other source of power for actuating the wire banding, tensioning, and tying mechanisms, 5 an elevator for raising the box 6 to a position where the bights of the wire are 15 twisted to secure the package, 7 a loop forming guideway for the wire and substantially surrounding the box to be banded, 8 a foot lever for moving the elevator 5, and 9 a reel of the wire 10 for banding the package.

The elevator 5 comprises a plurality of vertical parallel plates 11 spaced from each other to pass upwardly between conveyor rollers such as 12 fixedly carried by the framework of the machine 25 and substantially horizontally aligned with a series of conveyor rollers 13 over which a box is fed to the banding machine, and also aligned with another series of conveyor rollers 14 over which the banded box passes from the machine. In 30 Fig. 2 there is shown a box 15 raised by the elevator into wire tying position, and another box 16 on the conveyor rollers 13 ready for passage onto the elevator 5 after the box 15 has been banded and discharged from the machine.

35 As best seen in Figs. 2 and 3, the machine has three rollers 17, 18 and 19 interconnected by yokes such as 20 at each end of the rollers in such manner that the outside rollers 17 and 19 can be moved about the central and fixed roller 40 18, so that when the roller 17 is above the plane of the aligned rollers 12, 13 and 14, the roller 19 will be below such plane. One of the elevator plates 11 carries near its upper extremity a lateral extension such as 21 and which may 45 be a lug or pin, which extension contacts the yoke 20 when the elevator is moved downwardly, to bring about oscillation of the yokes 20. The spacing of the central roller 18 from the rollers 17 and 19 is preferably made unequal to cause 50 gravitational oscillation of the yokes, thereby normally urging the roller 17 upwardly into the position shown in Fig. 2 to intercept and stop the advancing movement of the box 16 toward the elevator, said roller 17 being moved downwardly to release said box 16 when the extension 55 21 on the elevator plate 11 in its downward movement contacts the yokes 20, this occurring only after the preceding box 15 has been banded. Preferably the series of conveyor rollers 60 13 are mounted in an inclined plane so that the urge of gravity may assist in moving the boxes toward this machine.

The elevator 5 has a depending arm 30 to which is pivoted as at 31 a lever 32 one end of which has a handle 33 and the other end of which is pivoted as at 34 to the frame of the machine. A bar 35 substantially parallel to the lever 32 has its opposite ends pivoted respectively as at 36 to the elevator arm 30, and as at 70 37 to the frame of the machine below the pivot 34 of said lever. Thus it will be understood from Fig. 1 that the elevator arm 30, the lever 32, the bar 35 and the frame of the machine, all constitute a parallel linkage whereby, when said linkage is oscillated, the elevator 5 will be raised 75

and/or lowered. The handle 33 is provided to permit manual assistance in the upward movement of the elevator.

A vertical lifter rod 38 has secured thereto a collar 39 near its lower extremity, said extremity passing through an opening in the inner end 40 of the foot lever 8 fulcrumed at 41, a second collar 42 being secured to the extremity of said lifter rod below the foot lever, the two collars being spaced from each other as desired to permit any necessary inoperative play or delayed action of the foot lever as will be pointed out later. Thus it will be understood that when the foot lever is depressed at one end, the other end 40 will contact the collar 39 and raise the 15 lifter rod 38.

A plate 43, near its lower end, is pivoted as at 44 to the lever 32 of the parallel linkage heretofore described, and at the upper end of said plate there is provided a lateral extension or ear 20 45 through which the lifter rod 38 slides, and around said lifter rod there is provided a relatively strong helical spring 46 whose ends bear against the collar 39 and the ear 45. Therefore it will be seen that when the foot lever 8 moves 25 the lifter rod upwardly, the spring 46 will be compressed and ultimately cause the plate 43 to move upwardly and in turn raise the elevator 5. The tension of the spring 46 is made such as to give the necessary yieldability and slightly delayed action in the raising of the elevator and hold the box 6 against the twister head under spring tension. A latch mechanism generally 30 identified by the numeral 47 in Fig. 1 is employed to hold the lifter rod 38 in elevated position as when said box is up against the twister head, said latch being released after the twisting operation and severance of the ends of the twisted bights of the wire, all as will be disclosed in more detail later on.

In Figs. 1 and 2 the twister mechanism is generally identified by the numeral 3 and comprises a train of gears for operating a slotted twister pinion, the detailed description and operation of which will appear hereinafter. In a vertical plane with the axis of the twister pinion, and rigidly carried by the frame of the machine is the more or less oval guideway 7, of substantially U-shape in transverse section, for forming the loop of banding wire, and from Fig. 1 40 it will be seen that this guideway substantially surrounds the box when in position to be banded, the open side of the U-shape guideway being inwardly directed toward the box so that, when the slack of the wire is drawn from the loop, the loop of wire may leave the guideway and come into surface contact with the box. In Fig. 2 there has been shown a duplication of the guideway 7 at 50, and a duplication of the twister mechanism 3 at 51, since in some cases it may be desired to provide a box simultaneously with plural bands, particularly if the boxes are large, it being understood that the second guideway 50 will be likewise positioned in the vertical plane with the axis of the twister pinion of the second 55 twister mechanism 51.

The reel 9 has its trunnions 52 disposed in the fork of a supporting bracket shown in Fig. 1 at 53, said bracket at its lower extremity being pivoted as at 54 to the framework of the machine and having the extremity of one arm of the fork adapted to be engaged by a hook or latch 55 carried by the machine framework, for holding the reel in more or less rigid position on the machine. When the reel has been emptied 60 70 75

of its wire, the bracket 53 is unlatched and swung about the pivot 54 to the dotted line position to receive a new reel of wire 9', and then the bracket is returned to its latched position shown in full lines in Fig. 1. The other arm of the bracket fork carries any suitable brake device generally indicated by the numeral 56 and adapted to bear against the periphery of the reel to create such a friction therewith as will prevent undue unwinding of the reel as the wire 10 is withdrawn therefrom, and said arm also carries a pair of friction rollers 57 and 58 between which the wire 10 passes in leaving the reel, said friction rollers being under spring tension as by forming their supporting member 59 of leaf spring material, all as will be readily understood.

An electric motor or other source of power is indicated by the numeral 4 for revolving the power shaft 60 having the worm 61 thereon driving the worm gear 62 keyed to a transverse shaft 63, and upon the front end of the shaft 63 is loosely mounted the gear 64 having secured thereto as by one or more pins 65, a feed roll 66, see Figs. 4 and 5. With particular reference to Figs. 5, 9 and 19 it will be seen that the shaft 63 also has keyed thereto the gear 67 enmeshed with the pinion 68 keyed to a stub shaft 69 substantially parallel with the shaft 63, and keyed to the opposite end of the shaft 69 is a gear 70 always enmeshed with the gear 64 which is loose on shaft 63. The gear 70 has secured thereto as by the pins 71 (see Fig. 4) a feed roll 72 cooperating with the feed roll 66. This pair of feed rolls may have their peripheries formed as desired but in the drawings they have been shown respectively as male and female rolls. The two shafts 63 and 69 are disposed in suitable bearings above the bed plate of the machine and the feed rolls 66 and 72 are of such diameters that the wire 10 will be in a substantially horizontal plane in lower tangential contact therewith.

Secured to the bed plate 2 of the machine but depending therefrom is a bracket 80 forming a substantial journal for a rock shaft 81, said shaft provided at one end with a T-head providing the oppositely extending arms 82 and 83 (see Fig. 4), the arm 82 carrying a transverse pin 84 upon which is loosely mounted the gear 85 adapted to enmesh with the gear 64, said gear 85 having secured thereto as by the pins 86 the feed roll 87 coaxing with the feed roll 66. The other arm 83 of the T-head carries a similar transverse pin 88 upon which is loosely mounted the gear 89 adapted to enmesh with the gear 70, said gear 89 having secured thereto as by the pins 90 the feed roll 91 coaxing with the feed roll 72. The opposite end of the rock shaft 81 is provided with any suitable means for giving oscillatory motion thereto but in Figs. 5 and 9 said rock shaft is illustrated as having its end formed as at 92 to separately key with the lower end of the lever 93 whose upper end is pivotally connected as at 94 with a push rod 95. The two pins 84 and 88 are below the bed plate of the machine and the feed rolls 87 and 91 carried thereby are of such diameters that their peripheries will be substantially tangential with the peripheries of the upper feed rolls 66 and 72 respectively.

Thus it will be understood from what has just been described that the transverse shaft 63 is constantly rotated by the power shaft 60 but that the feed roll 66 carried on the former has loose relation or non-rotation therewith. However, power from said shaft 63 is transmitted to the shaft 69 and this shaft has keyed thereto the

gear 70 carrying the feed roll 72. In other words, the gear 70 with its feed roll 72 is the only one of the feed roll gears that is positively driven from a constantly rotating shaft. But all four of the drive roll gears 64, 70, 85 and 89 are so mounted as to always be in mesh with each other, whereby rotation of the gear 70 by its shaft 69 will cause rotation of the other three gears. However, the lower pair of gears 85 and 89 is mounted on the rock shaft 81 wherefore, and with particular reference to Fig. 4, when the lever or arm 93 is in the position shown, there will be deeper enmeshment between the gears 64 and 85 than between the other vertical pair of gears 70 and 89. When, however, the push rod 95 is moved to the left as seen in said Fig. 4, lever arm 93 will slightly oscillate the rock-shaft 81 to reverse the depth of enmeshment between the two vertical pairs of gears just mentioned.

This oscillation is quite slight but is sufficient to cause the two vertical pairs of feed rolls to alternately pinch the wire 10 to cause movement of said wire either toward or away from the twisting mechanism. Consequently, when the parts are in the positions shown in Fig. 4, the left hand vertical pair of feed rolls, through their pinch, will cause the wire to be moved to the left in a direction from the reel to the twister, but when the pinch is transferred to the right hand vertical pair of feed rolls (through oscillation of rock-shaft 81) the wire will be moved to the right or in a direction from the twister to the reel, the wire 10 being shown in dotted lines because it is located in front of the feed gears.

The shaft 63, constantly rotated by the power shaft 60, has keyed or otherwise securely attached thereto the gear 100 enmeshed with the companion gear 101 transversely but loosely mounted on the shaft 102 (see Figs. 4, 5 and 9), said shaft 102 extending forwardly of the machine and having on its front end the upper gear of the twisting mechanism, said shaft 102 also controlling actuation of the device for holding the wire under tension during the twisting operation as well as controlling the release of the lifter rod 38. Therefore a clutch is provided for locking the helical gear 101 to the shaft 102.

This clutch comprises a member 103 secured to the shaft 102 for rotation therewith, said member having a bore 104 substantially parallel to the axis of said shaft and within which bore is slidably fitted a pin 105 having a projection 106 extending through the wall of the member 103 and engaged outside thereof in a slot 107 in the end of a bell crank 108 pivoted as at 109 to said member, a spring 110 being provided to normally urge the bell crank to oscillate in a direction to move said pin 105 to the right as seen in Fig. 10 and into a hole 111 formed in the face of the helical gear 101. In other words, since said helical gear is constantly rotated, the hole 111 in its face will move in a circular path about the stationary shaft 102 until it registers with the pin 105 which latter, under the urge of the spring 110, will snap into said hole and thereby lock the rotating helical gear 101 to the erstwhile stationary shaft 102 and cause rotation of said shaft.

An upstanding trip 112 is provided, the upper end of which is adapted to be moved into and out of the path of the end 113 of the bell crank 108 whereby, when the trip 112 is in the position shown in Fig. 10, said end of the bell crank, in the turning movement of the shaft 102, will strike the end of said trip and thereby cause oscillation of the bell crank to withdraw its associated pin 75

105 from the hole 111 of the helical gear 101 and thereby cause cessation of rotation of said shaft but permitting the helical gear to continue its constant rotation.

5 For protection, the helical gear 101 has a plate
114 pivotally secured to the face thereof pro-
vided with the hole 111, the free end of said
plate normally covering said hole, and said plate
has a portion of its inner edge upturned to pro-
10 vide the abutment 115, see Figs. 10 and 11. Thus,
through any possible failure of the trip 112 in
functioning, or operating at the required time,
the pin 105 might protrude from its bore and
cause an undesired engagement with the helical
15 gear 101, but the plate 114 is provided to cover
said hole and require said pin to contact the
inner edge of said plate to move said plate out
of its hole-covering position, the abutment 115
being provided to assure movement of said plate.
20 A spring 116 is provided to assure normal coverage
of the hole by said plate.

To insure the stopping of the rotation of the shaft 102 in proper position, and to hold the shaft in such position until the next engagement of the clutch 103 with the helical gear 101, the rear end of shaft 102 has keyed thereto a cam 117 provided with a peripheral indentation 118 adapted to be engaged closely by a roller 119 mounted at one end of a bar 120 whose other end is freely pivoted as at 121 to a portion of the framework or gear casing of the machine, said bar being under the urge of a relatively strong coil spring 122 operating as shown in Fig. 5 to force the roller 119 into the indentation 118.

35 Referring particularly to Figs. 6, 7 and 8, there is illustrated therein the twister mechanism and its associated parts. 130 and 131 designate two vertically parallelly spaced walls supported by the bed plate of the machine, between which pair
40 of walls the twister gear train is disposed, the front end portion of the shaft 102 being journaled in the upper portion of wall 131, with the main driving gear 132 of said train keyed to the extremity of said shaft. This main driving gear
45 is adapted to enmesh with an intermediate gear 133 whose shaft 134 is supported by at least one of said walls, which gear 133 is enmeshed with a second intermediate gear 135 whose shaft 136 is supported in both of said walls, and the gear
50 135 is enmeshed with the twister pinion 137 whose trunnions are supported in said walls or in plates attached thereto, and the gear ratio may be made as desired according to the size of the twisted knot desired, preferably the two intermediate
55 gears being of the same size.

To the outer face of wall 130 is secured a jaw plate 138 provided with the wire receiving slot 139 in its extending end, and to the outer face of the other wall 131 there is secured a similar jaw plate 140 having the wire receiving slot 141 in its extending end, the slots 139 and 141 of both plates being as usual of a width equal to the diameter of the wire 10 and being aligned with the axis of the twister pinion 137 in the usual manner whereby, when the two bights of the wire are placed into the full depth of said slots, said wires will substantially coincide with the axis of the twister pinion for formation of the twisted knot shown in Fig. 20 and said jaw plates will limit the extent of such knot.

To the outer face of the jaw plate 138 is pivoted as at 142 a cutter 143 under tension of a spring 144, the upper end 145 of said cutter adapted to be actuated by a cam 146 formed on the protruding end of shaft 136 of the intermediate

twister gear 135. Thus it will be understood that in the rotation of said gear 135 its shaft cam 146 will oscillate the cutter 143 about its pivot and cause the lower end 147 thereof to move upwardly and cut one of the bights of the wire in close proximity to the end of the twisted knot, the edge of the slot 139 and the edge of the cutter end 147 cooperating in shearing effect on said bight. (See Fig. 7). 5

To the outer face of the other jaw plate 140 is pivoted as at 148 a cutter 149 under tension of a spring 150, the upper end 151 of said cutter adapted to be actuated by a cam 152 formed on the opposite protruding end of shaft 136 of the intermediate twister gear 135. Thus it will be understood that in the rotation of said gear 135 its shaft cam 152 will oscillate the cutter 149 about its pivot and cause the lower end 153 thereof to move upwardly and cut the other bight of the wire in close proximity to the opposite end of the twisted knot, the edge of the slot 141 and the edge of the cutter end 153 cooperating in shearing effect on said bight. (See Fig. 8). The two cutters are actuated simultaneously and suitable stops such as the pin indicated at 154 in Fig. 8 are provided for each cutter against the tension of its spring and to position each cutter with respect to its actuating cam.

Journalized in the two walls 130 and 131 is a rock shaft 160 whose ends extend beyond said walls, and on one of said ends is secured a depending arm 161 in sliding contact with the outer face of the wall 130, the lowermost end of said arm normally occupying a position to the rear of the twisted knot in the twister pinion (see Fig. 7), and to the other of said ends of the rock shaft 160 is secured a similar depending arm 162 in sliding contact with the outer face of the other wall 131, the lowermost end of this arm 162 likewise normally occupying a position to the rear of the twisted knot (see Fig. 8). These two depending arms serve as "kickers" in that they forcibly eject from the twister pinion, and from the jaw plates 138 and 140, the twisted knot after the formation thereof and after the cutters have operated in a manner now to be described.

Likewise secured to the rock shaft 160 is another arm 163 whose end is formed with an opening to permit passage therethrough of a stem 164 pivotally attached as at 165 to a bar 166 the 50 lowermost end of which is loosely mounted on the rock shaft 160. A coil spring 167 is disposed about said stem and confined as shown in Fig. 8 between the arm 163 and the bar 166. The upper end 168 of said bar is adapted to contact with a 55 cam 169 formed on or attached to the shaft 102 whereby, upon rotation of the shaft 102, said cam will oscillate the bar 166 and place said spring under considerable and increased tension. A latch or hook 170 of leaf spring nature is provided for receiving and holding the end 168 of said bar when the latter is moved downward, the end of said bar snapping under the yieldable hook. A coil spring 171 is provided tending to 60 retain the "kicker" arms 161 and 162 against a 65 shoulder such as 172 of the walls with which they are associated, and in the normal position (above referred to) behind the twisted knot. Oscillation of the bar 166 does not occur until after the start of the twisting operation, and in fact starts 70 at a time between the final two registrations of the slot of the twister pinion and the slots 139 and 141 of the jaw plates, wherefore it is impossible for said depending arms to "kick" the bights of wire out of the twister mechanism until 75

the final registration of the slot of the twister pinion with the slots of the jaw plates. During this final registration, the tension of the spring 167 is so great as to cause oscillation of the rock shaft 160 by virtue of the tensioning arm 163, overbalancing the tension of the spring 171, and consequently actuating the "kicker" arms to eject the twisted knot from the twister pinion. The end 168 of the bar 166 remains latched under the hook 170 during this operation, but is released subsequently as will be disclosed in the operation of the machine. The arm 163 may be joined to the "kicker" arm 162, if desired, to constitute a bell crank.

15 The main driving gear 132, of the twisting gear train, is a mutilated gear in that it has a number of teeth omitted to give an intermittent or delayed action to the intermediate gear 133 and therefore to the twister pinion. As previously stated the gear ratio may be as desired but, for example, if three twists are desired in the knot then the twister pinion 137 must be given three complete revolutions, and if this pinion has ten teeth then the intermediate gears 20 must each have thirty teeth, and the mutilated main driving gear 132 must have no more than thirty teeth so that the knot may be formed in the one revolution of the main gear. Consequently the remainder of said gear is formed 25 with a smooth peripheral edge 180 aligned with the roots of the teeth so that the teeth of the intermediate gear 133 will have no coaction with this blank portion of the main gear.

An arcuate plate 181 is secured to a face of 30 the mutilated gear in the region of such blank portion, the outside radius of said plate being equal to the maximum radius of said gear, with the outer peripheral edge 182 of said plate aligned with the tips of the teeth of said gear as clearly shown in Fig. 7. From the outer face of said plate extend pins or projections 183 and 184 which are tangential to the peripheral edge 182 of said plate, and the outside edge of said plate is not continuously circular but is provided as at 35 185 with an inwardly extending portion or hollow, all for purposes presently to appear.

To one face of the intermediate gear 133 there is attached a block 186 of a thickness at least equal to the thickness of the arcuate plate 181 carried by the mutilated gear, see Figs. 6, 7 and 20, this block being disposed in the same plane with said plate. This block has a concavely formed outer edge 187 adapted to substantially slidingly contact with the peripheral edge 182 of 40 said arcuate plate, said concave edge terminating in the points 186 and 189 of such distance from the axis of the gear 133 that they may extend into the path of the projections 183 and 184 carried by the mutilated gear. A plate 190 covers the outer face of the block 186 and is of substantially the same configuration thereof except that the edge of said plate has a hump 191 at a position intermediate the points 188 and 189 of said block, said hump being of a radial 45 extent to extend likewise into the path of said projections.

When the locked clutch 103 and helical gear 101 have caused rotation of the shaft 102, the trip 112 intercepts the end 113 of the clutch lever 70 108 thereby withdrawing the locking pin 105 from the hole 111 in said helical gear (see Fig. 10), but the constantly rotating helical gear is loosely mounted on said shaft wherefore said shaft comes to rest and when this occurs, the twisting mechanism is in the position shown in 75

Figs. 6, 7 and 8 with the slot of the twister pinion registering with the slots 139 and 141 of the jaw plates, and ready to receive the wire preparatory to forming the next twisted knot. The parts are held in this position by virtue of the cam 117 and its roller detent 119, see Fig. 5. After subsequent operations of feeding the wire around the package, drawing the slack out therefrom and placing the wire under tension, which operations will be later described, the trip 112 will be moved 10 from under the clutch lever thus causing the clutch pin 105 to be urged into position for engaging the hole of the helical gear when it next comes around, and again locking the clutch and gear to cause rotation of shaft 102.

In this rotation the stud or projection 186, carried by the arcuate plate of the mutilated gear, will first strike the hump 191 of the plate 190 of the intermediate gear 133, and said stud and said hump are so positioned on their respective gears that, when they so contact, the intermediate gear 133 will be correctly positioned for its teeth to be engaged by the first tooth 192 of the mutilated gear. This is made possible by the point 189 of the block 186 riding off of the periphery of the arcuate plate just prior to engagement of said stud with said hump. The mutilated gear by its teeth then causes rotation of the gear train, giving the necessary number of twists to the wires in the twister pinion by the 25 time that the last tooth 193 of said mutilated gear is ready to leave, or break engagement with, the teeth of the intermediate gear.

At this time the point 189 of the block carried by the intermediate gear will be under the arcuate plate 181 of the mutilated gear, and any possible retrograde movement of the intermediate gear 133, resulting from any cause, is prevented by sliding engagement between the concave surface 187 of said block and the periphery of said arcuate plate. Continued rotation of shaft 102 causes the other stud 183 of the mutilated gear to strike the hump 191 of the plate 190 and to rotate the intermediate gear 133 slightly to provide a correspondingly slight over-twist in the knot. 30 The purpose of this over-twist is to compensate for the inherent springiness or tension in the knot resulting from the twisting operation, thus insuring the required number of twists in the knot when ejected from the twister pinion; this over-twist also reduces to a minimum the frictional contact of the outer surface of the completed knot with the inner surfaces of the twister pinion slot and the slots of the jaw plates, when the knot is ejected.

Because of this slight over-twisting movement given to the gear 133, the hollow 185 is provided in the periphery of the arcuate plate 181 to receive the point 189 rocked thereinto by this movement, but after said stud 183 passes said hump 60 then said point rides out of said hollow and on to the remainder of the circular periphery of said plate; this gives a slight retrograde movement to the gear 133 which is automatically transferred to the twister pinion, and this retrograde movement brings registration of the twister pinion slot with the jaw plate slots and eases the tension on the over-twisted knot. However, when this occurs the parts will be in the position shown in Fig. 7 and at this time the trip 112 will have 65 operated the clutch 103 to cease rotation of the shaft 102.

Adjacent and substantially parallel to the wall 130 of the twister head there is a rock shaft 200 having secured to one end thereof a depending 75

5 dog 201 whose foot is serrated or roughened to grip the end of the wire and hold the same against an anvil 202 aligned with the slot of the twister pinion, see Figs. 6 and 7. Said rock shaft has thereabout a coil spring 203 to normally urge said dog in holding position on said wire, said dog having on its outer face a plate 204 whose lower extremity is outwardly deflected, said plate serving to guide the end of the wire under said dog 10 when said wire is fed through the slot of the twister pinion. Said rock shaft has a pin 205 extending laterally therefrom toward the intermediate twister gear 133, said pin adapted to be engaged by a companion pin 206 mounted on the 15 face of said gear whereby, in the rotation of said gear, the two pins will coengage and the pin 205 will be moved downwardly and thus cause a clockwise rotary movement of said rock shaft (see Fig. 6) resulting in a release of the end of the 20 wire by the holding dog 201. The rock shaft is journaled in an ear 207 carried by said wall 130.

Pivottally mounted in said ear 207 is a depending latch member 208 under the urge of a spring 209, the lowermost end of said latch aligned with the anvil 202 and the slotted twister pinion, and having formed thereon a shoulder or recess 210 so positioned as to receive a lower corner of the holding dog 201 when said dog is oscillated into its wire releasing position. A side of said anvil 30 serves as a stop for the end of said latch (see Fig. 6).

The opposite end of the rock shaft 200 is journaled in a lateral extension 211 of the wall 130 and carries at its extremity a detent 212 adapted to engage the tooth 213 of a second pivot-detent 214 under the upward urge of a leaf spring 215, said detent 214 being disposed substantially within an opening 216 formed in one end of a square bar 217 adapted to slide in correspondingly squared openings in the walls of the twister head, said bar being rigidly attached as by the pin 218 to a block 219 one vertical surface of which abuts the gear train housing wall 131 as a stop for limiting movement of said block in one direction (see Fig. 12).

In the upper portion of said block there is formed a circular bore for slidably receiving therethrough one end of the push rod 95, the extreme end of said rod being slidably journaled 50 in said wall 131. Said push rod has attached thereto a collar 220 against which abuts one end of a coil spring 221 disposed about said rod, the other end of said spring abutting against the opposite vertical surface of the block 219. Said 55 block has attached thereto the latch hook 170 adapted to engage the end of the bar 166 for controlling actuation of the "kickers" 161 and 162. Said push rod also has attached thereto a second collar 222 receiving thereagainst one end of a second coil spring 223 disposed about said push rod, the opposite end of said spring abutting against a wall 224 associated with the housing for the motor worm gear drive for this machine, said wall 60 224 slidably supporting said push rod.

65 Pivoted as at 230 to the extension 211 of the wall 130 of the twister head is a bell crank 231 to the extremity of the upper arm of which is attached an operating rod 232 (see Figs. 1 and 7) extending downwardly and attached to the foot lever 8 through a portion of the framework of the machine, there being provided a spring 233 for normally urging this operating rod upwardly, the extremity 234 of the lower arm of said bell crank being positioned to contact the front end 75 of the square sliding bar 217. Within the bell

crank is housed a spring actuated pin 235 operating against a shoulder of the detent 212 carried by the rock shaft 200 (see Fig. 12).

Thus it will be understood that when the foot pedal is depressed, the bell crank 231 will be oscillated and its arm 234 will cause a movement of the push rod 95 to the right as seen in the drawings thereby oscillating the arm 93 (see Figs. 4 and 12) and causing pinch relationship of the feed rolls 66 and 87 upon the wire 10 to move said wire in a direction from the reel to the twister mechanism, and that the push rod will be held in its right hand position (as illustrated in Fig. 12) by engagement of the detent 212 of the rock shaft 200 with the tooth 213 of the detent 214 carried by 15 said square bar, the push rod then being under the tension of both of its springs 221 and 223. When the rock shaft 200 is oscillated counter-clockwise as seen in Fig. 12, the two detents will be disengaged, whereupon the push rod 95 will move to the left as seen in the drawings under the urge of its springs and cause reverse oscillation of the arm 93 to release the pinch action on feed rolls 66 and 87 but to bring about pinch action between the other vertical pair of feed rolls 72 and 92 (Figs. 4 and 9) and thereby cause the wire to move in a direction from the twister mechanism to the reel, this movement of the wire resulting in the removal of the slack from its loop about the box to be banded. 25 30

Attached to the pin 218 which holds the square bar 217 to the block 219, is one end of a trip rod 236 the opposite end of which is slidably supported in the wall 224 of the motor drive housing, said rod having two collars thereon, the collar 237 serving as a stop for one end of a coil spring 238 disposed about said rod, the other end of said spring bearing against one end of a weight 239 slidable on said rod, the other collar 240 serving as a stop for the opposite end of said weight (see Figs. 12 and 13). The spring 238 is of only sufficient strength to move the weight back against the rear stop collar 240, said weight being of sufficiently great transverse sectional area that a portion of an end thereof will contact the trip 45 112 associated with the clutch 103 by means of which power is transmitted from the constantly rotating helical gear 101 to the shaft 102 for operating the twister mechanism. The lower end of the trip 112 is loosely bracketed as at 241 to the bed plate of the machine, and a coil spring 242 normally urges said trip to the right as seen in Fig. 13 up against the end of the clutch 103 so that the upper end of said trip may be in the path of the arm 113 of the clutch bell crank 103 50 55 (see Fig. 10).

Thus it will be understood from Figs. 12 and 13 that, when the two detents 212 and 214 are disengaged, the push rod 95 under the urge of its strong springs, will snap to the left as seen in said drawings, and this movement will cause the block 219 to have quick motion to the left which in turn is imparted to the rod 236 and the weight 239 thereon, said weight continuing its movement to the left due to the inertia thereof and against the slight tension of the light spring 238, said weight striking the trip 112 with sufficient force to move the latter out from under the arm 113 of the clutch bell crank to permit the pin 105 of said clutch to move into position for engagement with the hole of the constantly rotating helical gear 101. Thereafter the tension of the trip spring 242 will be sufficient to return the trip 112 to a position against the clutch 103 so that the upper end of said trip will be in the path of 75

the end 113 of the clutch bell crank so that the latter will be engaged by said trip, subsequently, and cause oscillation of the clutch bell crank to disengage the clutch pin 105 from its locking position in the hole of the helical gear 101. The weight spring 238 is by-passed by the trip 112, wherefore the weight 239 may again be urged against its stop collar 240 ready for a repetition of the movement just above described.

As above brought out, the vertical pair of feed rolls 66 and 87 constitute the means for feeding the wire from the reel toward the twisting mechanism, and the other vertical pair of rolls 72 and 91 constitute the means for drawing the slack out of the wire loop around the box to be banded, and the gears 64, 85, 70 and 89 attached to said feed rolls are always in mesh with each other and are driven by the shaft 69 from the constantly rotating shaft 63, which has keyed thereto the helical gear 100. This drive is preferred since it provides a ratio through the gears 67 and 68 (Fig. 19) such as to cause rapid operation of the feed rolls, which is essential in automatic speed machines. This helical gear 100 carries a pin 250 on its face which, in the rotation of said gear, is adapted to engage the hook 251 formed at the end of a tensioning lever 252, said lever being in the form of a bell crank pivoted as at 253 in a slot 254 of a gripper bar 255 which is yieldably supported by the bed plate of the machine.

The pivot 253 of the tensioning lever 252 passes through one end of a plate 256 whose other end is laterally extended to form an ear 257 provided with an opening for passage therethrough of the round shank portion 258 of the otherwise rectangular gripper bar 255 which portion 258 receives thereabout a pair of coil springs 259 and 260 the tension of which may be varied and made as desired by the nuts 261 and 262 threaded on said portion, see Fig. 15. In other words the spring 259 is disposed between the nut 261 and the ear 257 of the plate 256, and the other spring 260 is disposed between the other nut 262 and the bracket 263 carried by the bed plate of the machine.

Thus, after the arm 93 has been oscillated to release the feed-in rolls 66 and 87 from pinching contact with the wire, and to bring the pair of feed-out rolls 72 and 91 into pinching relation on the wire, the slack of the wire loop will be drawn out, and the wire brought into close contact with the sides of the box to be banded. Near the end of this operation, the pin 250 on the helical gear 100 will engage the hook 251 of the tensioning lever 252 and cause said lever to be moved to the right as seen in Fig. 13, this movement causing the pivot pin 253 to move toward the end of its slot 254 with concurrent movement of the plate 256 to the right against the tension of its spring 259. Tensioning of the spring 259 ultimately overcomes the tension of the spring 260 and thereby causes movement to the right of the gripper bar 255.

The left hand end of this gripper bar is downwardly directed and carries a pivoted dog 264 which, when rocked by this right hand movement of said bar, grips the wire against the floor of a slide 265 operating in the guideway 266 therefor (Fig. 16) and thereby gives the necessary tension to the wire about the box preparatory to the formation of the twisted knot, the holding dog illustrated in Fig. 14 being employed to hold the coil end of the wire to prevent the feed-out rolls 72 and 91 from drawing the wire out of the machine after the cutters have operated. A roller cam

267 mounted on the shaft 102 urges the tensioning lever 252 downwardly to insure gripping action of the dog 264 during the tensioning operation. The slide 265 is preferably trough-shaped and a tube 268 is preferably provided in alignment with the open portion of said slide, said tube being rigidly mounted in the frame of the guideway 266 and provided for the purpose of insuring alignment of the wire 10 with the tensioning dog 264. A stop 269 may be provided for the bell crank 252 for raising the hooked end 251 of the latter and holding the same in position for registrable contact with the pin 250 of the miter gear 100.

Referring to Fig. 14, the shaft 102 is provided with a cam 275 adapted to oscillate a lever 276 pivotally supported at 277 on the bed plate of the machine and having an extending arm 278 threadingly receiving a screw 279 the lower end of which is adapted to engage a dog 280 mounted on the pivot 277, said dog engageable with the tensioned wire in a suitable slotway in the bed plate 2 of the machine. After the wire has been tensioned about the box by the mechanism just previously described, the cam 275 operates the lever 276 to bring the dog 280 into tight holding relationship on the tensioned wire during the twisting of the knot and in the interim between the actuation of the cutters and the actuation of the feeding-in rolls, thus retaining the coil end of the wire in the machine. On the side of safety a bar 281 may be provided receiving thereagainst a side of the lever 276 for counteracting a lateral thrust on said lever that may be caused by the tension of the tensioned wire.

The device for holding the lifter rod 38 is shown in Fig. 17 and comprises a plate 282 substantially horizontally disposed and pivotally mounted at one end as at 283 to the bed plate 2 of the machine. This plate has an opening therethrough near its free end to permit passage therethrough of said lifter rod, said opening being of such shape and dimension that, when the plate is in its lowered position as seen in said figure, a relatively sharp edge 284 of said opening will have a pinch or biting effect into the surface of said rod and prevent downward movement of said rod. The extreme free end of said plate rests upon the end of one arm 285 of a bell crank pivotally supported as at 286 upon the bed plate of the machine, the other arm 287 of said bell crank carrying a roller 288 at its extremity which roller is adapted to be engaged by a cam 289 mounted upon the shaft 102. Thus it will be understood that after the knot has been twisted and the ends of the wire cut off adjacent the twisted knot, and the twisted knot ejected from the twister mechanism, the cam 289 will operate said bell crank to raise the plate 282 from its gripping position and thereby release the lifter rod 38 which is then free to fall, the fall of said rod permitting the lowering of the banded box.

In case the box to be banded has considerable weight it may be desirable to augment the action of the foot lever with automatic means for raising the box to banding position and therefore, the apparatus illustrated in Fig. 18 is provided. The lifter rod 38 has attached thereto a bracket 290 pivotally supporting the lower end of a rack 291 extending upwardly and placed under the urge of a spring 292 tending to force said rack in a direction to the left as seen in said drawings. or in a direction away from the rack gear 293 mounted for rotation with a worm gear 294 en-

meshed with the worm 295 carried by an extension of the power shaft 60, said gear 293 disposed within a housing a portion of which is cut away as indicated at 296 to expose the teeth of said gear to the rack 291, said gear rotating in the direction of the arrow to exert a lifting movement to said rack when the latter is moved into enmeshment therewith. The push rod 95 carries a collar 297 so positioned as to swing the rack 291 into a vertical position as shown in full lines in the drawings to bring about engagement of the rack and the rotating gear, it being understood that said gear is constantly rotating due to its driving connection from the motor.

15 Thus it will be understood that when the foot lever is depressed, the bell crank 231 will be oscillated (Fig. 12) to cause movement of the push rod 95 to the right as seen in the drawings, and this movement of the push rod through the collar 297 moves the rack 291 into gear engaging position whereupon the gear will cause upward movement of said rack and thereby assist in the upward movement of the lifter rod 38, and corresponding upward movement of the box 6 into the correct position for formation of the twisted knot in the encircling and securing wire band. The teeth of the rack terminate so that when the box has been lifted to this position there will be no enmeshment with the gear 293, the lifting rod 38 then being gripped by the device shown in Fig. 17 and held thereby in its elevated position. Upon disengagement of the detents 212 and 214, through oscillation of the rock-shaft 200 to be described later in the operation of this machine, push rod 95 is released and moves to the left under the urge of its spring 223, thereby permitting the rock 291 to swing to the left under the urge of its spring 292 into the dotted line position shown in Fig. 18 and out 40 of engagement with the gear 293.

The operation of this machine is as follows: A box is positioned on the elevator 5 as indicated at 6 in Fig. 1 and then the foot lever 8 is depressed causing upward movement of the lifter rod 38 and through said rod corresponding upward movement of the elevator to bring the box into the position shown in Fig. 18 substantially against the twister head, said lifter rod automatically being latched in its raised position by the plate 282 shown in Fig. 17. Downward movement of the foot lever causes oscillation of the bell crank 231 the lower arm 234 of which causes the push rod 95 to be moved to the right as seen in Fig. 12 and then (only however in the initial starting of the machine) the dog 201 is moved manually to the left as seen in Fig. 6 to bring its lower corner onto the shoulder 210 of the holding latch 208. This movement of the dog 201 oscillates its rock shaft 200 against the tension of its spring 203 to cause the detent 212 of said rock shaft to engage the detent 214 associated with the push rod 95 to hold said push rod in its right hand position.

This movement of the push rod to the right oscillates the arm 93 to bring the vertical pair of feed rolls 66 and 87 into play to feed the wire 10 from the reel through the slotted twister pinion around the loop guideway 7 and again through the slotted twister pinion so that the free end of the wire strikes the lower end of the latch 208 and pushes it slightly to the left as seen in Fig. 6, and this movement of the latch releases the dog 201 from the shoulder 210 of said latch, whereupon said dog is free to snap (under the urge of the rock shaft spring 203) into the posi-

tion shown in Fig. 6 to grip the end of the wire and hold the same against the anvil 202. The dog 201 and its latch 208 are so positioned that the wire in first passing through the twister pinion, passes to the side of said dog and its latch, but after forming the loop in the guideway 7 the free end of the wire in passing the second time through the twister pinion assumes a position along side the first bight of the wire and is in alignment with said dog and latch.

When the dog 201 is thus released from its latch 208, its movement into holding position just described on the end of the wire, causes oscillation of the rock shaft 200 sufficient to disengage the detents 212 and 214 thus permitting the push 15 rod 95 to snap quickly to the left as seen in Fig. 12 under the urge of its spring 223, and thereby oscillate the arm 93 to release the vertical pair of feeding-in rolls 66 and 87 but to bring the pair of vertical feeding-out rolls 72 and 91 into 20 play to pinch the wire and move said wire in a direction toward the reel, thereby drawing the slack out of the loop of wire around the box.

When the push rod 95 thus snaps to the left, the sliding weight 239, on the rod 236 associated with said push rod, strikes the trip 112 to move the upper end thereof from under the arm 113 of the bell crank 108 of the clutch member 103 (see Fig. 10) and said bell crank oscillates under the urge of its spring to bring the clutch pin 105 30 into position for engagement with the hole 111 of the constantly rotating helical gear 101, and when said pin is engaged in said hole, the shaft 102 will be rotated with said helical gear and actuate the twister mechanism. Just before the 35 twister mechanism operates the slack will have been withdrawn from the wire loop about the box and the tensioning lever 252 actuated to cause the wire to be tensioned around the sides of the box.

The twisting mechanism provides a slight over-twist whereby the slot of the twister pinion is moved slightly beyond registration with the slots of the jaw plates 138 and 140, thereby imprisoning the twisted knot, and at this time the 45 "kickers" will have been fully tensioned (Fig. 8) by the operation and latching of the bar 166, the holding dog 280 will have been actuated by the cam 275, and the cutters 143 and 149 will have been actuated to sever the ends of the two bights 50 of the wire adjacent the ends of the twisted knot. Also at this time the pin 206 carried by the intermediate twister gear 133 will have engaged and moved the pin 205 to oscillate the rock shaft 200 thus releasing the dog 201 from the severed extreme end of the wire, and moving said dog into latched position on the shoulder 210 of the latch member 208. When the twister pinion moves backward from its over-twist position, its slot will register with the slots of the jaw plates, and the 55 twisted knot will be "kicked" out and cleared of said jaws during the lowering of the banded box. After the kickers have operated to release the twisted knot from the twister head, the cam 289 will cause release of the lifter rod 38 and permit the lowering of the elevator and its banded box.

At the completion of the twisting of the knot, the clutch 103 will have rotated to bring the end 113 of its bell crank 108 into engagement with the upper end of trip 112 and thereby cause oscillation of said bell crank to withdraw clutch pin 105 from the constantly rotating helical gear 101, resulting in cessation of rotation of the shaft 102. When the next box is brought to the elevator and raised as hereinbefore described, the 75

holding dog 280 Fig. 14 will have been released to permit the next feeding-in action of the pinch rolls 66 and 87, and the operations just described will be repeated. The various parts are designed and so positioned as to bring about the proper coordination and timing of the various mechanisms as should be evident.

From the foregoing description it will therefore be seen that by this invention there is provided an automatic wire tying machine provided with a wire tying head which includes the train of gears for rotating the twister pinion, the cutters, and the "kickers" for ejecting the twisted knot from the tying head. Below this tying head there is a box receiving floor comprising the plurality of spaced rollers 12, 17 and 18, between which the box supporting plates 11 are adapted to pass, the roller 17 movable into a position to intercept the next following box, and one of said supports having the projection 21 for removing the roller 17 from its box intercepting position. These plates 11 constitute the elevator for raising the box to the tying head, and lever means are provided for lifting said elevator, said means controlling the actuation of the tying head through the provision of the push rod 95 and its connections for shifting the feed rolls, the elevated box being retained against the tying head by the latch device generally identified by the numeral 47. Mechanical means for assisting in the box raising are shown in Fig. 18 as including the constantly energized pinion 293 and the pivoted rack 291 engageable therewith.

The wire feeding means is constantly energized and comprises the four feed rolls 66 and 87 arranged as one vertical pair and the rolls 12 and 91 arranged as the other vertical pair, all four rolls being constantly geared together as shown in Fig. 4 for actuation in unison, each roll mounted upon a shaft, but only the roll 12 secured to its shaft and that shaft 69 constantly rotated in one direction only, the wire 10 being disposed substantially horizontally between the rolls of each vertical pair. The two lower rolls are supported in a yoke which is rockable by the arm 93 actuated by the push rod 95 thereby constituting means for shifting the lower rolls toward and away from their upper rolls without disconnecting their intergeared relationship, resulting in pinching effect of one vertical pair of rolls on the wire for feeding the wire to and around the box to be banded, and then alternately resulting in pinching effect of the other vertical pair of rolls on the wire for feeding the wire in a direction away from the box to remove the slack thereabout.

With particular reference to Fig. 1 it will be seen that the bracket 53 for supporting the reel 9 of wire is so constructed and pivotally supported on the framework of the machine as to constitute a lever for raising a heavy full reel of wire from the shop floor into wire feeding position upon the framework. In other words a full reel of wire can be rolled, in the position indicated at 9', to the unlatched bracket so that the reel trunnions will readily enter the fork of the two upper arms of said bracket, and then the extremity of the lowermost arm raised to swing both reel and bracket into the full line positions shown in this figure of the drawings. This is an important feature since it is not uncommon for some wire reels to weight several hundred pounds.

Lastly it is desired pointed out that this machine is admirably suited for handling wires of different transverse cross sectional shapes, round

wire having been used for many years. An important feature is the adaptability of this machine to oval wire or wire having a major and a minor axis, the wire being fed flatwise over the bed of the machine to and through the twister so that the bights of the wire which are lapped in said twister are side by side with their major axes coaligned or in the same horizontal plane. In forming the twist, the bights are rolled in a direction transverse to said major axes whereupon, in the resultant knot, the edges of one bight substantially contact the edges of the other bight. In other words the two bights are maintained in the twister pinion slot in flat sidewise contact instead of in superposed contact of one flat bight over the other bight. The splicing of the oval wire may be stated in other words as consisting of twisting the two sidewise contacting bights along their minor axes around each other until the edges of their major axes coincide and their edges are in contact with each other, resulting in the creation of a longitudinal resistance in the knot to a pulling strain, far beyond any similar resistance in a knot as heretofore formed with round wire.

It is obvious that those skilled in the art may vary the details of construction and arrangements of parts without departing from the spirit of this invention and therefore it is desired not to be limited to the exact foregoing description except as may be required by the claims.

What is claimed is:

1. In a wire tying machine for banding boxes the combination of a wire tying head; a box receiving floor disposed below said head and comprising a plurality of spaced members; an elevator comprising box supports adapted to pass between said members; and means to lift said elevator to raise a box from said floor to said tying head.

2. In a wire tying machine for banding boxes the combination of a wire tying head; a box receiving floor disposed below said head and comprising a plurality of spaced members; an elevator comprising box supports adapted to pass between said members; and means to lift said elevator to raise a box from said floor to said tying head, said means controlling actuation of the tying head.

3. In a wire tying machine for banding boxes the combination of a wire tying head a floor for receiving a box from a supply of boxes, said floor disposed below said head and comprising a plurality of spaced members, one of said members movable into a position to intercept the next following box; an elevator comprising box supports adapted to pass between said members, one of said supports adapted to remove the one of said floor members from its intercepting position; and means to lift said elevator to raise a box from said floor to said tying head.

4. In a wire tying machine for banding boxes the combination of a wire twisting mechanism; a box receiving floor disposed below said mechanism and comprising a plurality of spaced members; an elevator comprising box supports adapted to pass between said members; means to lift said elevator to raise a box from said floor to said tying mechanism; and means for holding the lifting means in its elevated position, said holding means releasably controlled by said mechanism.

5. In a wire tying machine for banding boxes the combination of a wire tying head; a box receiving floor disposed below said head and com-

prising a plurality of spaced members; an elevator comprising box supports adapted to pass between said members; and means to lift said elevator to raise a box from said floor to said 5 tying head, said means including a constantly energized pinion and a pivoted rack engageable therewith.

6. In a wire tying machine for banding boxes the combination of wire feeding means constantly 10 energized; wire twisting means; and means for shifting the wire feeding means into positions first for feeding the wire to and around the box to be banded and through the wire twisting means, and second for feeding the wire in a re- 15 verse direction to remove the slack from the loop thereof around the box and to tension the wire prior to operation of the wire twisting means.

7. In a wire tying machine for banding boxes the combination of wire feeding means comprising a plurality of coacting wire pinching members, one only of said members constantly 20 energized; wire twisting means; and means for shifting certain other members of the wire feeding means into positions first for feeding the 25 wire to and around the box to be banded and through the wire twisting means, and second for feeding the wire in a reverse direction to remove the slack from the loop thereof around the box and to tension the wire prior to operation 30 of the wire twisting means.

8. In a wire tying machine for banding boxes the combination of wire feeding means comprising a plurality of members constantly interconnected for coaction in unison, said members adapted to exert pinching action upon the 35 wire disposed therebetween, one only of said members constantly energized; wire twisting means; and means for shifting certain other members of the wire feeding means into positions first for feeding the wire to and around the box to be banded and through the wire twisting 40 means, and second for feeding the wire in a reverse direction to remove the slack from the loop thereof around the box and to tension the wire prior to operation of the wire twisting means.

9. In a wire tying machine for banding boxes the combination of wire feeding means comprising a plurality of feed rolls constantly 45 geared together for coaction in unison, said feed rolls adapted to exert pinching action upon the wire disposed therebetween, one only of said feed rolls constantly energized; wire twisting means; and means for shifting certain other feed rolls of the 50 wire feeding means into positions first for feeding the wire to and around the box to be banded and through the wire twisting means, and second for feeding the wire in a reverse direction to remove the slack from the loop thereof around 55 the box and to tension the wire prior to operation of the wire twisting means.

10. In a wire tying machine for banding boxes the combination of a source of operating power; wire feeding means constantly driven from said 60 source; wire twisting means; a clutch between said wire twisting means and said source; and means for shifting the wire feeding means into positions for feeding the wire in opposite directions, said shifting means controlling said clutch.

70 11. In a wire tying machine for banding boxes the combination of a source of operating power; wire feeding means constantly driven from said source, said means comprising four feed rolls 75 constantly geared together, each roll mounted upon a shaft, one only of said rolls secured to

its shaft and that shaft rotated from said source; wire twisting means; a clutch between said wire twisting means and said source; and means for shifting certain of the rolls of the wire feeding means into wire pinching positions with respect to others of said rolls for feeding the wire in opposite directions, said shifting means controlling said clutch. 5

12. In a wire tying machine for banding boxes the combination of a source of operating power; 10 wire feeding means constantly driven from said source, said means comprising four feed rolls constantly geared together and disposed substantially in the form of a square thus providing two upper rolls and two lower rolls, the two lower 15 rolls shiftable toward and away from the two upper rolls, each roll mounted upon a shaft, one only of said rolls secured to its shaft and that shaft rotated from said source; wire twisting means; a clutch between said wire twisting 20 means and said source; and means for shifting the lower rolls of the wire feeding means into wire pinching positions with respect to the upper rolls for feeding the wire in opposite directions, said shifting means controlling said clutch. 25

13. In a wire tying machine for banding boxes the combination of a source of operating power; wire feeding means constantly driven from said source; wire twisting means including a single operating shaft; a clutch between said shaft and 30 said source; means for shifting the wire feeding means for movement of the wire in opposite directions, said shifting means controlling said clutch; and means operated from said shaft for controlling actuation of a wire tensioning device, 35 for holding the tensioned wire, and for energizing ejectors of the twisted knot from the wire twisting means.

14. In a wire tying machine for banding boxes the combination of a source of operating power including a constantly rotating member; wire 40 feeding means constantly driven from said source; wire twisting means including a single operating shaft upon which said member is loosely mounted; a clutch between said shaft and said member; means for shifting the wire feeding means for movement of the wire in opposite directions, said shifting means controlling said 45 clutch; and means operated from said shaft for controlling actuation of a wire tensioning device, 50 for holding the tensioned wire, and for energizing ejectors of the twisted knot from the wire twisting means.

15. In a wire tying machine for banding boxes the combination of a source of operating power; 55 wire feeding means constantly driven from said source; wire twisting means including a single operating shaft; a clutch between said shaft and said source; means for shifting the wire feeding means for movement of the wire in opposite 60 directions, said shifting means actuating a member the inertia of which controls said clutch in one directional movement of the shifting means; and means operated from said shaft for controlling actuation of a wire tensioning device, 65 for holding the tensioned wire.

16. In a wire tying machine for banding boxes the combination of a source of operating power; wire feeding means constantly driven from said source; wire twisting means including a single 70 operating shaft; a spring actuated clutch between said shaft and said source and including a trip member for controlling said clutch; means for shifting the wire feeding means for movement of the wire in opposite directions, said shifting 75

means actuating a slidable weight the inertia of which controls said clutch in one directional movement of the weight; and means operated from said shaft for controlling actuation of a 5 wire tensioning device, for holding the tensioned wire, and for energizing ejectors of the twisted knot from the wire twisting means.

17. In a wire tying machine for banding boxes and provided with a wire twisting head the combination of wire feeding means comprising a set 10 of four feed rolls constantly geared together for actuation in unison, each roll mounted upon a shaft, one only of said rolls secured to its shaft and that shaft constantly rotated in one direction 15 only, said rolls disposed in the form of a square thus providing two vertical pairs of rolls, the banding wire disposed substantially horizontally between the rolls of each vertical pair; and means for shifting the lower rolls toward 20 and away from their upper rolls without disconnecting their intergeared relationship, said shifting means comprising a rockable yoke supporting the lower rolls and connections for rocking said yoke to bring about pinching action upon 25 the wire between said vertical pairs of rolls, such pinching action alternating between said pairs first to cause travel of the wire in a direction toward said head for the purpose of forming a loop of the wire around the box to be banded, 30 and then to cause reverse travel of the wire to draw the wire loop tightly about the box preparatory to the twisting action of said head.

18. In a wire tying machine for banding boxes the combination of wire feeding means; wire 35 tensioning means; wire twisting means; and means for moving a box to the twisting means, said moving means controlling actuation of all of the other said means.

19. In a wire tying machine for banding boxes the combination of wire feeding means; wire 40 tensioning means; wire twisting means; and means for moving a box to the twisting means, said moving means automatically inaugurating actuation of all of the other said means.

20. In a wire tying machine for banding boxes and provided with a wire twisting head the combination of wire feeding means comprising a set 45 of four feed rolls constantly geared together for actuation in unison, each roll mounted upon a shaft, one only of said rolls secured to its shaft and that shaft constantly rotated in one direction only, said rolls disposed in the form of a square thus providing two vertical pairs of rolls, the banding wire disposed substantially horizontally 50 between the rolls of each vertical pair; and means for shifting the lower rolls toward and away from their upper rolls without disconnecting their intergeared relationship to bring about pinching action upon the wire between 55 said vertical pairs of rolls, such pinching action alternating between said pairs first to cause travel of the wire in a direction toward said head for the purpose of forming a loop of the wire around the box to be banded, and then to 60 cause reverse travel of the wire to draw the wire loop tightly about the box preparatory to the twisting action of said head.

21. In a wire tying machine for banding boxes the combination of wire feeding means constantly 65 energized; wire twisting means; means for shifting the wire feeding means into positions first for feeding the wire to and around the box to be banded and through the wire twisting means, and second for feeding the wire in a re- 70 verse direction to remove the slack from the loop of wire around the box; and means for tensioning the wire around the box after the removal of such slack, said tensioning means independent of said feeding means.

22. In a wire tying machine for banding boxes the combination of wire feeding means constantly energized from a rotating shaft; wire 75 twisting means; means for shifting the wire feeding means into positions first for feeding the wire to and around the box to be banded and through the wire twisting means, and second for feeding the wire in a reverse direction to remove the slack from the loop thereof around the box; and means for tensioning the wire around the box after the removal of such slack, said tensioning means independent of said feeding means but controlled by a pin rotating with said shaft.

23. In a wire tying machine for banding boxes the combination of wire feeding means constantly energized from a rotating shaft; wire 20 twisting means; means for shifting the wire feeding means into positions first for feeding the wire to and around the box to be banded and through the wire twisting means, and second 25 for feeding the wire in a reverse direction to remove the slack from the loop thereof around the box; and means for tensioning the wire around the box after the removal of such slack, said tensioning means independent of said feeding means and including a hook and a pin, the pin rotating with said shaft, and the hook movable into engagement with said pin.

24. In a wire tying machine for banding boxes the combination of wire feeding means constantly energized; wire twisting means; means for shifting the wire feeding means into positions first for feeding the wire to and around the box to be banded and through the wire twisting means, and second for feeding the wire in a reverse direction to remove the slack from the loop thereof around the box; and means for tensioning the wire around the box after the removal of such slack, said tensioning means independent of said feeding means and comprising 35 a member for subjecting said tensioning means 40 to a predetermined pressure.

25. In a wire tying machine for banding boxes the combination of wire feeding means constantly energized; wire twisting means; means 50 for shifting the wire feeding means into positions first for feeding the wire to and around the box to be banded and through the wire twisting means, and second for feeding the wire in a reverse direction to remove the slack from the loop 55 thereof around the box; and means for tensioning the wire around the box after the removal of such slack, said tensioning means comprising a spring controlled member the pressure of which is adjustable in accordance with the strength of 60 the banding wire used.

26. In a wire tying machine for banding boxes the combination of wire twisting means; means to feed a wire around the box to be banded and through the twisting means, and then to remove 65 the slack from the loop of wire around the box; and means for tensioning the wire around the box after the removal of such slack, said tensioning means independent of said feeding means.

27. In a wire tying machine for banding boxes 70 the combination of wire twisting means; means to feed a wire around the box to be banded and through the twisting means, and then to remove the slack from the loop of wire around the box; and means for tensioning the wire around the 75

box after the removal of such slack, said tensioning means independent of said feeding means and comprising a member for subjecting said tensioning means to a predetermined pressure.

5. 28. In a wire tying machine for banding boxes the combination of wire twisting means; means to feed a wire around the box to be banded and through the twisting means, and then to remove the slack from the loop of wire around the box; 10 and means for tensioning the wire around the box after the removal of such slack, said tensioning means comprising a spring controlled member the pressure of which is adjustable in accordance with the strength of the banding wire 15 used.

15. 29. In a wire tying machine for banding boxes the combination of a source of operating power; wire feeding means constantly driven from said source; wire twisting means including a single 20 operating shaft; a clutch between said shaft and said source, said clutch controlled by said wire feeding means; and means for tensioning the wire around the box, said tensioning means independent of said feeding means and controlled 25 by said shaft.

30. 30. In a wire tying machine for banding boxes the combination of a source of operating power; wire feeding means constantly driven from said source; wire twisting means including a single operating shaft; a clutch between said shaft and said source, said clutch controlled by said wire feeding means; and means for tensioning the 35

wire around the box, said tensioning means independent of said feeding means and including a hook and a pin, the pin carried by a constantly rotating member, and the hook controlled by said shaft and movable into engagement with said pin. 5

31. In a wire tying machine for banding boxes the combination of a source of operating power; wire feeding means constantly driven from said source; wire twisting means including a single 10 operating shaft; a clutch between said shaft and said source, said clutch controlled by said wire feeding means; and means for tensioning the wire around the box, said tensioning means independent of said feeding means and comprising 15 a member for subjecting said tensioning means to a predetermined pressure said member controlled by said shaft.

32. In a wire tying machine for banding boxes the combination of a source of operating power; 20 wire feeding means constantly driven from said source; wire twisting means including a single operating shaft; a clutch between said shaft and said source, said clutch controlled by said wire feeding means; and means controlled by said 25 shaft for tensioning the wire around the box, said tensioning means comprising a spring controlled member the pressure of which is adjustable in accordance with the strength of the banding wire used. 30
